(57) **CLAIM**

The ornamental design for a firearm trigger guard, as shown and described.

DESCRIPTION

FIG. 1 is a top, back, left perspective view of a first embodiment of a firearm trigger guard in accordance with the present disclosure.

FIG. 2 is a bottom, front, left perspective view of the firearm trigger guard of FIG. 1.

FIG. 3 is a front view of the firearm trigger guard of FIG. 1. FIG. 4 is a back view of the firearm trigger guard of FIG. 1. FIG. 5 is a right side view of the firearm trigger guard of FIG. 1.

FIG. 6 is a left side view of the firearm trigger guard of FIG. 1.

FIG. 7 is a bottom view of the firearm trigger guard of FIG. 1.

FIG. 8 is a top view of the firearm trigger guard of FIG. 1. FIG. 9 is a top, front, left perspective view of the firearm trigger guard of FIG. 1, shown in an environment of use. FIG. 10 is a top, back, left perspective view of the firearm trigger guard of FIG. 1, shown in an environment of use. FIG. 11 is a bottom, front, left perspective view of the firearm trigger guard of FIG. 1, shown in an environment of use.

FIG. 12 is a bottom, back, left perspective view of the firearm trigger guard of FIG. 1, shown in an environment of use.

FIG. 13 is a left side view of the firearm trigger guard of FIG. 1, shown in an environment of use.

FIG. 14 is a top, front, left perspective view of a second embodiment of a firearm trigger guard in accordance with the present disclosure.

FIG. 15 is a top, back, left perspective view of the firearm trigger guard of FIG. 14.

FIG. 16 is a bottom, front, left perspective view of the firearm trigger guard of FIG. 14.

FIG. 17 is a bottom, back, left perspective view of the firearm trigger guard of FIG. 14; and,

FIG. 18 is a left side view of the firearm trigger guard of FIG. 14.

The broken lines in the Figures illustrate portions of the article that form no part of the claimed design.
